UNITED STATES PATENT OFFICE

ALFRED B. HOUTZ, OF ELIZABETH CITY, NORTH CAROLINA

APPARATUS FOR APPLYING HOOPS AND/OR LINERS TO BARRELS

Application filed December 11, 1928. Serial No. 325,187.

This invention relates to apparatus for winding flexible wooden strips, such as barrel hoop stock, to hoop or circular form on barrels and nailing the strips to the barrels as the barrels are rotated to coil or wind the strips thereon, and by reference to winding and nailing the strips on the barrels, I include winding and nailing the strips both exteriorly and interiorly of the barrels to provide the barrels with exterior surrounding hoops and/or interior circular hoop-like liners, particularly barrel bottom supporting liners; and the objects and nature of the invention will be understood by those skilled in the art 10 in the light of the following explanations of the accompanying drawings that illustrate what I now believe to be the preferred mechanical expression or embodiment of my invention from among other forms, arrangements and combinations within the spirit and 15 scope thereof.

An object of the invention is to provide apparatus for supporting a headless barrel, i. e. a barrel body open at both ends, for rotation step by step, to wind thereon, either or both externally and internally, thin narrow flexible wooden strips and to nail the same thereto to provide each barrel with one or more exterior wood hoops securely nailed thereto, and/or one or more interior end coiled or circular wooden hoop-like liners securely nailed thereto, particularly to provide at the bottom end of the barrel an internal annular supporting ledge or shoulder to support the barrel bottom or head and if need be, to provide an anchorage for the nails securing such head.

A further object of the invention is to provide barrel nailing machines of commerce, 40 with improved means for rotating headless barrels step by step and winding wooden strips thereon and nailing the same thereto.

A further object of the invention is to provide a barrel nailing machine with mechanism and means for guiding flexible wooden strips into a rotary barrel for coiling to hoop form therein and nailing thereto to provide the barrel end with an internal hoop-like liner.

50 With the foregoing and other objects in

view, my invention consists in certain novel arrangements and/or combinations of features, parts or mechanisms, and in certain novel features of structure as more fully described and specified hereinafter.

55

Referring to the accompanying drawings, forming a part hereof:—

Fig. 1 is a front elevation, somewhat diagrammatically showing a barrel nailing machine equipped with apparatus of my invention operating on a wooden barrel shown partially in vertical section and also operating on wooden strips shown partially broken away, to form exterior hoops and an internal liner on and nailed to the barrel.

65

Fig. 2 is a detail side elevation, showing the barrel in end elevation and the wooden strips in edge elevation.

Fig. 3 is a detail horizontal section, the barrel being shown in horizontal section.

70

Fig. 4 is a detail front elevation, dotted lines indicating the operative position of the barrel, the barrel supporting horn or arm not being shown.

Fig. 5 is a detail side elevation, the barrel in end view being indicated by dotted lines.

Fig. 6 is a detail detached perspective of the guide for the wooden hoop forming strips.

Figs. 7 and 8, are perspective views of the end stop for the inner or bottom-receiving end of the barrel and the guide for the wooden strips to be coiled within and nailed to the barrel to form the internal hoop-like liner.

Fig. 9 is a detail perspective of the free end portion of the barrel supporting arm.

85

I show, in part, any suitable or conventional barrel hoop nailing machine. For instance, I have shown in part, a well known automatic barrel hoop nailing machine of the "Morgan" type, although I do not wish to limit all features of my invention to the "Morgan" type of machine, as my invention can be adapted to other barrel hoop securing machines.

90

The barrel hoop nailing machine that I happen to illustrate for the purpose of showing and explaining what I now believe to be the preferred adaptation of my invention, embodies a base 1, for a rigid upright frame 2, on which a barrel support or carrier is ver-

100

tically adjustable by means of screw adjusting devices 3.

This barrel support or carrier is arranged at the front of the machine, and embodies a transversely arranged horizontal base portion 4, and a top transversely-arranged horn or arm 5, arranged a distance above the base 4, and at one end joined rigidly to the adjacent end of base 4, by the rigid upstanding neck portion 6, so that the base 4, horn 5, and neck 6, constitute a strong rigid unit, with the horn free at one end and separated from the base portion, to longitudinally receive a barrel *a*, open at both ends, applied and removed over the free end of the horn, with the barrel resting on the top longitudinal side of the horn and hanging therefrom and free to be rotated thereon, and with the horn extending throughout the length of the barrel. At its front end, the horn 5, is usually provided with a pair of idler rolls 7, to travel against the upper portion of the interior surface of the front end of the barrel to center and steady the barrel on the horn.

The frame 2, extends upwardly in rear of the barrel supporting horn, and at its upper part carries one or more nail hoppers or containers and nail feeding mechanism 8, say of the Morgan or any other suitable type, from which nail conduits 9, lead to vertically reciprocating nail drivers or nailing chucks 10, arranged above the horn 5, all of a well known or other suitable type. These nailing chucks are carried and actuated by a transversely-arranged horizontally disposed nailing head 11, slideable vertically on the upright frame 2, and including the lower bars 11^a. The nailing head 11, is also guided by the uprights 11^b, rising from the arms 12, normally fixed to the frame 2.

The nailing head 11, (and parts actuated thereby) is reciprocated by suitable gearing and crank means (not shown) for instance as disclosed by Morgan Patent No. 1,605,054, Nov. 2, 1926. Means for operating the nail feeding and distributing mechanism 8, is not shown, but various means can be employed for this purpose, for instance, such as disclosed by said Morgan patent.

In the apparatus of my invention, the horn 5, is formed and arranged to receive the barrel, open at both ends, either end foremost, and in the particular example illustrated, nail anvils or clinching blocks 13, 13^a, are removably clamped in the top longitudinal slot 5^a, of the horn, below the nailing chucks 10, respectively, and so that the top longitudinal portion of the barrel *a*, rests thereon and is backed thereby while the barrel is at rest during the nailing operation, and so that the barrel slides thereover during each rotating or advancing step of the barrel. In this example, I show anvil dies or nail clinching blocks 13, at the opposite ends of slot 5^a, under the opposite end por-

tions of the barrel to clinch the inner ends of nails securing end hoops on the barrel, while intermediate anvil dies or nail clinching blocks 13^a, are located under the barrel bilge to clinch the inner ends of the nails securing, in this example, the two bilge hoops. As the bilge hoops are of greater diameter than the end hoops, I prefer to provide nail chucks for the bilge hoops that will drive two nails at each nailing stroke, one in advance of the other in the direction of barrel rotation, and hence the blocks 13^a, are each provided with two series of nail clinching grooves 13^b to simultaneously clinch two spaced nails. The various blocks 13, 13^a, are each, preferably, formed with at least one series of grooves, each groove having a bevelled or rounded floor to cause the pointed ends of the nails to bend or curl backwardly and upwardly and bury their points in the wood of the barrel or in the wood strip secured thereto. If so desired, the end nail drivers or chucks 10, can also be arranged to simultaneously drive two or more nails through the end hoops, or through the bottom end hoop and the liner, or the center nailers can be arranged to drive, at each nail driving stroke, one or more nails through the bilge hoops.

The horn 5, and adjacent members are arranged, to permit a barrel, open at both ends, to be longitudinally slipped onto the horn bottom end foremost, i. e. before the bottom has been applied to the bottom end of the barrel and while the staves are temporarily held together in barrel form by one or more exterior surrounding wire or other temporary hoops. The bottom end of the barrel will hence surround the base portion of the horn, remote from the free end thereof, and hence, I provide at the base end or portion of the horn means to limit the inward longitudinal movement of the barrel body on the horn and to aid in guiding and steadyng the barrel body during nailing and rotary movements. For this purpose, I show a vertically arranged segmental stop and guide plate 15, normally fixed to and rising from the base portion of the horn 5, and preferably having a flat vertical elongated abutment face to abut the end edges of the barrel staves throughout a substantial number of degrees of the circle of the barrel end, and along which the barrel end slides during barrel rotation. This guide and stop plate 15, can be secured to and mounted on the horn, preferably for adjustment longitudinally of the horn, by any suitable means, although I happen to show, for this purpose a horizontal base 15^a, projecting rearwardly from plate 15, to fit on the top of the horn, and having elongated slots 15^b, to receive the bolts by which said plate is normally clamped in fixed position on the horn. The plate 15, and its base, are preferably slotted see 15^c, Figs. 7 130

and 8, to straddle and expose the adjacent nail clinching die or block 13, to the nails driven radially of the barrel and down through its end.

- 5 In order to confine the barrel on the horn against objectionable longitudinal movement during nailing and rotation and to hold the barrel bottom end to the desired sliding guiding contact with plate 15, I provide barrel 10 guiding stop means for cooperation with the open top or outer end of the barrel on the horn, and render such means movable from the path of the barrel, to permit application and removal of barrels to and from the horn. 15 For this purpose, in the example shown, I provide a segmental stop and guide plate 16, which in normal operative position, is vertically arranged in front of or outside the top or outer end of the barrel, above the free end 20 of the horn, with the edge of the barrel end in sliding engagement with the flat inner vertical face of plate 16. This plate 16, beyond the outer end of the barrel, performs approximately the same stop and guiding 25 functions as the plate 15, at the inner end of the barrel. The plate 16, is fixed to the free end of and is carried by a vertically swingable bracket or arm 16^a, pivoted at 16^b, to the bottom portion of the front or free end of 30 the horn, to swing on a horizontal transverse axis toward and from the free end of the horn, from inoperative forwardly projecting position, Fig. 9, to upright operative position, Figs. 1 and 2. When the plate 16, is in the 35 position of Fig. 9, the barrel can be slipped onto and from the horn. After a barrel has been slipped onto the horn, the stop plate is swung to upright position against the end edge of the top portion of the barrel, in which 40 position, the plate is detachably or removably held by any suitable means, such as detent or latch 17, detachably engaging a cross bar 16^c, of the swingable stop.
- 45 Means is provided for advancing or rotating the barrel on the horn step by step, with the barrel at rest during the nailing operations. For instance, I show a periodically driven rotary shaft 18, arranged longitudinally of and approximately parallel with the 50 horn 5, and to the rear thereof and carried by brackets 19, fixed to the horn and provided with suitable bearings for the shaft. This shaft is arranged longitudinally of and within the barrel on the horn between the 55 horn and the rear side of the barrel and between the upper and lower portions of the barrel. The shaft 18, has fixed thereon barrel gripping and driving wheels 20, preferably tapered to approximately conform to 60 the barrel bilge or taper and having roughened peripheral surfaces to frictionally or grippingly engage the inner surface of the barrel near its ends to rotate the barrel when the barrel is held to or pressed forwardly 65 radially against said driving wheels. For

this last mentioned purpose, I show a laterally movable presser shaft 21, having idler presser rolls 22, arranged approximately parallel with the barrel driving shaft 18, and to the rear thereof, between the barrel on the horn and the frame uprights 2. The idler presser rolls 22, are opposite the driving wheels 20, so that when the idler shaft 21, at the exterior of the barrel, is bodily pressed forwardly radially of the barrel, its idler 70 rolls 22, will contact the exterior of the rear portion of the barrel and press the barrel laterally forward into tight barrel rotating contact with the rotating barrel driving rolls 20.

75 Various means can be provided for controlling the position of and applying forward pressure to the idler rolls 22, although in the example illustrated, I show the presser shaft 21, located in the lower ends of hangers 23, fixed to and depending from rock shaft 24, mounted to rock in brackets 25, fixed to frame 2. A lever 26 is fixed to and extends rearwardly from rock shaft 24, and at its rear end this lever is provided with weight 26^a. 80 85 to normally rock shaft 24, to hold the presser rolls in operative forward position to co-operate with driving wheels 20. Any suitable means, such as hand lever 27, can be provided to lift weighted lever 26, and carry the 90 presser rolls 22, rearwardly from operative position.

95 Suitable means are provided to rotate the barrel feed or rotating shaft 18, step by step, and to assure that the barrel remains at rest 100 during the nailing operation. For instance, in the example illustrated, I extend the inner end of barrel feed shaft 18, beyond the bottom or inner end of the barrel and on said extended shaft end, I fix a ratchet wheel 18^a, and to the vertically reciprocatory nailing head 11, I secure a depending hanger 28, at its lower part carrying a depending swingable pawl 29, pivotally coupled to said hanger and loosely embracing and vertically movable with respect to ratchet wheel 18^a, and having a cross pin 29^a, to successively engage the teeth of the wheel and rotate the wheel a step at a time on the upward movement of the pawl and to slip down loosely over the wheel 105 without rotating the same on the downward movement of the pawl. Thus on the downward nailing stroke of head 11, the barrel feeding means remains at rest, while on the upward return stroke of the nailing head 110 and chucks, the barrel feeding means is operated to advance the barrel a step. This apparatus is peculiarly arranged and designed to carry out my method of hooping barrels 115 by feeding more or less flexible wooden hoop stock onto the barrel by rotation of the barrel employing the barrel as the mandrel on which to form hoops from lengths of stock, and nailing such stock strips to the barrel at intervals until the ends of the strips meet and 120 125 130

are secured, thereby winding and securing the flat more or less thin wooden strips to endless circular hoop form on the barrel.

In the example illustrated, I show the machine, arranged and constructed to simultaneously wind four comparatively thin narrow flexible wooden strips or lengths of wood hoop stock *b*, exteriorly around the barrel and nail the same thereto at intervals, to provide the barrel with four exterior completely encircling hoods nailed thereto. The four strips *b*, are fed from the front rearwardly over and transversely of the barrel in the direction of rotation of the top portion of the barrel, and the rear ends of all the strips are first placed on top of the barrel under the appropriate nailing chucks which are then operated to nail the strip ends to the barrel, thereafter the step by step rotation of the barrel feeds the strips rearwardly thereto and thereon and the strips are secured in hoop form by the nailing operations intervening between the barrel feeding steps or rotations, until the front ends of the strips overlap the rear or first secured ends and are secured by the final nailing operation. To maintain the proper positions, spacing and straight line feed of the strips *b*, to the barrel top, I provide a strip support and guide 30, above the barrel and a distance in front of the several nailing chucks, with separate guideways alined with the nailing chucks, respectively, for the several strips *b*, and in the example shown, these guideways are established by fixed pins 31, upstanding from the guide and support 30. The guide 30, in this example, consists of a stiff bar having upturned ends 30^a, fixed to the frame arms 12, whereby the bar 30, is normally held in a fixed position approximately parallel with the horn 5, and above the elevation thereof and consequently above the barrel thereon and a distance in advance of the nailing chucks 10, and this bar is preferably bowed to approximately conform to the barrel bilge or taper. As shown, the strips *b*, are upheld by and feed transversely across said bar in their respective guideways. In this connection, it will be noted, that if so desired the barrel can be rotated step by step by hand or otherwise, when the machine is carrying out the hereinbefore described hooping method, and I do not wish to limit myself in all respects to the particular barrel rotating means disclosed hereby.

I follow, in effect, the foregoing hooping method in providing the barrel with an internal hoop within an end thereof, to provide the barrel with a liner which can be employed to support the barrel bottom and provide an anchorage for the bottom securing nails.

The machine disclosed provides means for guiding a comparatively thin flexible flat wooden strip *c*, into the barrel through its open bottom or inner end in position for

winding or coiling against the inner surface of the end portion of the barrel and in position to be secured to the staves by the same nails that secure the adjacent exterior end hoop to the barrel, thereby providing a circular ledge or shoulder within the barrel end, an interior hoop, secured by the nails securing the surrounding exterior end hoop.

To thus support and guide the strips *c*, I provide a tubular or longitudinally hollow strip guide 33, at the inner side of and fixed to the barrel stop plate 15, (Fig. 8) and locate this guide at the lower front portion of said plate so as to be within the barrel on the horn and in front of and below the nail clinching block 13, within the stop plate slot 15^e. This tubular guide 33, preferably curves downwardly and forwardly and is open at its opposite ends with its upper or outlet end arranged in front of, close to and approximately below the level of the working face of said adjacent block 13. One end of the strip *c*, is inserted in the lower end of said guide and the strip is threaded upwardly therethrough so that the advancing end of the strip will be directed by the guide upwardly and rearwardly over said block 13, and be pressed down on the top working face of said block by the under surface of the portion of the barrel upheld by said block. This starting end of the strip *c*, pressed between said block 13, and the inner surfaces of the barrel, and located directly under the adjacent nailing chuck 10, and the exterior end hoop strip *b*, is secured to the barrel end by the nail that secures the end of the end hoop strip *b*, which nail is driven by the chuck down through strip *b*, the barrel, the strip *c*, and against block 13, which clinches the pointed end of the nail upwardly back into strip *c*. The starting end of the strip *c*, is thus first nailed to the barrel, as are the starting ends of strips *b*, and thereafter, the forward rotary advancing movements of the barrel draws and feeds the various strips *b*, *c*, onto the barrel, either the outer or the inner circumference thereof, to circular or hoop form as hereinbefore described.

While the apparatus is peculiarly adapted for using the barrel as the mandrel or form on which to simultaneously wind strips of hoop stock of wood or other material, to circular hoop form both within and without the barrel, by rotation of the barrel, and to secure such strips by nailing, yet I do not wish to so limit all features of my invention, as the apparatus can be employed to nail hoops previously completed in circular form and slipped longitudinally to the desired position on the barrel for subsequent nailing, and the internal liner or hoop can be formed and secured within the barrel, as hereinbefore described, whether or not the exterior hoops are formed on or previously applied to the barrel.

The term "barrel", is employed herein in a generic sense to include wooden casks, kegs, and containers. Various changes, departures, modifications and/or additions, can be resorted to without departing from the spirit and scope of my invention as expressed by the claims, and hence I do not wish to limit my invention to the constructions illustrated.

10 What I claim is:

1. In apparatus for securing hoops to barrels; in combination, nail driving and clinching mechanism; means for rotatably supporting a barrel body; and means for guiding a flexible hoop strip length into the barrel through an open end thereof for winding to circular hoop form against the inner surface of the barrel by the rotation of the barrel and for nailing to the barrel by said mechanism.

20 2. Barrel nailing apparatus, including, a relatively fixed support for a barrel body hung on and rotatable around said support on a longitudinal axis; nailing means arranged exteriorly of the barrel for applying hoop securing fasteners thereto; and a hoop strip supporting guide secured to said barrel support to guide the strip into the barrel for winding and securing therein to form a liner.

25 3. Barrel nailing apparatus, including a barrel body support for carrying the body for rotation on a longitudinal axis; means for driving hoop securing fasteners through hoop stock to secure the same to the barrel body, and a normally fixed guideway for slidably receiving lengths of flexible wood strips movable therethrough in the direction of rotation of the barrel, said guideway arranged to guide hoop stock through an open end of the barrel for securing therein by said means to provide the barrel with an end liner.

40 4. Barrel nailing apparatus, including a barrel body support for carrying the body for rotation on a longitudinal axis; means for driving hoop securing fasteners through hoop stock to secure the same to the barrel body, and a normally fixed guideway for slidably receiving lengths of flexible strips movable therethrough in the direction of rotation of the barrel, said guideway arranged in alignment with said means and the hoop location on the barrel, a relatively-fixed anvil for said fasteners being provided within the barrel body near an open end thereof, said guide being located near said anvil to direct said strips against the inner surface of said body opposite said anvil for winding around the inner surface of the body and securing thereto to form an inner liner in the body.

45 5. Barrel nailing apparatus, including a supporting horn to rotatably receive a barrel body open at both ends, said horn providing a nail anvil for location within a barrel end within the plane of the barrel exterior end hoop location; nailing means exteriorly of the barrel for driving nails through the end hoop

and barrel body and against said anvil, and guiding means for directing flexible strips in the direction of barrel rotation against the inner surface of the barrel end in the plane of said hoop location for winding, by the barrel rotation, into hoop form within the barrel end and securing by said nails passing through said outer hoop, and the body.

6. Barrel nailing apparatus, including a horn to support an open end barrel body for rotation, a normally fixed end stop for said body, a nail anvil on said horn adjacent to said stop to lie within the body and back the same; an end hoop nailer at the exterior of the body opposite said anvil; and a guide for lengths of flexible strips, normally fixed with respect to said horn to lie within the barrel, the outlet end of said guide arranged to direct the strips in the direction of body rotation, between the working face of the anvil and the inner surface of the body, for securing to the inner surface of the body by the nails forced through the body and said strip and against said anvil, by the nailer.

7. A barrel nailing machine, including a stationary horn for rotatably supporting a barrel body with the body surrounding the horn and hanging from the longitudinal top thereof; a barrel end stop and guide fixed to and rising from the base end of the horn, and a corresponding barrel body stop and guide arranged at and mounted on the free end of the horn, said front stop being vertically movable to and from upright operative position, and depressed inoperative position to permit a barrel open at its ends to be slipped either end foremost longitudinally onto and from the horn around said front stop when said stop is in said depressed position.

8. A barrel nailing machine, including a nailing mechanism; a relatively fixed barrel body supporting horn; a barrel body rotatable shaft arranged adjacent to the horn to lie longitudinally within the barrel body on the horn, and provided with wheels to engage the inner surface of the body to rotate the body; means for rotating said shaft; and movable presser means at the exterior of the barrel body for pressing said body laterally into operative contact with said wheels.

9. A barrel nailing machine including a horn to longitudinally receive an open end barrel and support the barrel hanging from the horn top; said horn at its inner end having a barrel guide and stop and at its outer end having barrel engaging idler rolls and a front barrel stop; means for rotating the barrel step by step on the horn; and nailing mechanism.

10. Barrel nailing mechanism including a barrel supporting horn to longitudinally receive an open end barrel and support the same hanging from the top of the horn for rotation transversely across the horn top; a rotary shaft supported adjacent to the horn and

below the level of the horn top to be located within the barrel when on the horn; said shaft having wheels to engage the inner surface of the barrel to rotate the same on the horn; periodically movable nailing mechanism for operating on the barrel on the horn; mechanism for periodically rotating said shaft; and means for cooperating with the barrel and said wheels to yieldingly hold the inner surface of the barrel in operative contact with said wheels.

Signed at Elizabeth City, North Carolina,
this 8th day of Dec., 1928.

ALFRED B. HOUTZ.
